UNITED STATES PATENT OFFICE.

MICHAEL S. HOUSKEN, OF SAN FRANCISCO, CALIFORNIA.

RAILWAY SWITCH.

Application filed April 16, 1925. Serial No. 23,608.

The invention relates generally to improvements in railway track construction. More particularly the invention has to do with the rail elements included in switches, frogs, crossovers, and the like.

The general object of the invention is to provide for increasing the stability and durability of switches, frogs and the like without adding to the complexity, material and installation costs of the structures. In fact the present invention is so constructed and designed that its use greatly simplifies such construction, materially reduces installation and maintenance costs and, at the same time, 15 actually increases the effectiveness of switch structures from the standpoint of safety.

The above and other objects are accomplished by instrumentalities pointed out in the following specification.

20 The invention is clearly defined in the claims.

A satisfactory embodiment of the invention is illustrated in the accompanying drawings forming part of the specification and 25 in which—

Figure 1 is a plan view of an embodiment of my invention showing the same in use in connection with a switch frog.

Figure 2 is a detail cross section on the 30 line 2—2 of Figure 1.

Figure 3 is a view similar to Figure 2 on the line 3—3 of Figure 1.

Figure 4 is a view similar to Figure 3 on the line 4—4 of Figure 1.

35 Figure 5 is a detail side elevation of one end portion of the movable rail member.

Figure 6 is a bottom plan view of Figure 5.

Figure 7 is a plan view of a turnout switch 40 constructed in accordance with my invention.

Figure 8 is a cross section on the line 8—8 of Figure 7.

Figure 9 is a cross section on the line 9—9 45 of Figure 7.

Figure 10 is a cross section on the line 10—10 of Figure 7, with the parts in one position of adjustment, and

Figure 11 is a view similar to Figure 10, 50 showing the parts in another position of adjustment.

In carrying out the present invention in connection with a frog, as shown in Figure 1, the use of switch points, guard rails, 55 flangeways is eliminated, and I have substituted therefor the elements of an ordinary

stub frog which is indicated generally by *a*. As shown, this element has the uniform proportions of an ordinary track rail and is, therefore, of greater strength throughout its 60 length than a frog having varying proportions such as a tapered frog. The member *a* is interposed in the space occupied by the ordinary frog between the ends of the rail sections 5 and 6 of the main track, for instance, and the ends of the sections 7 and 8 of the crossing track, and in this position it is held against displacement by creeping of the track sections 5, 6, 7 and 8, or by the expansion or contraction of these members, 65

70 by means of a tie *b* which extends across the space between the ends of the rail sections. The tie *b* is formed of metal and its end portions are fixedly secured to the rail sections so that these are in effect rigidly 75

connected one to the other into a comparatively integral structure. In order to accomplish the aforesaid result, the tie *b* may be constructed in various forms according to 80

the type or location of track in which the frog *a* is to be employed. For purposes of 85 illustration I have shown the tie *b* as comprising two metallic lengths 9 and 10 arranged on the remote sides of the sections 5,

6, 7 and 8, and extending over the crossties 11 to which they are connected in any preferred manner as by plates 12 bolted or spiked to the ties as indicated by 13 and secured to the outwardly extending base portions 14 of the ties by rivets or their equivalents 15. The upright side portions 16 of 90

the ties extend upwardly to the underside of the heads of the rail sections and to points a trifle below the head of the stub frog and are bolted to the web 17 of the rail sections 95

by bolts, one of which is shown in Figure 2 and indicated by 18, which bolts are secured by the usual nuts 19. The stub frog *a* is pivotally connected at its central portion to the tie *b* by a pivot pin 20 which passes through an elongated opening in the web 21 of the stub frog and through the upright side portions 16 of the tie, as clearly shown 100

in Figure 4. An enlargement 22 at the middle portion of pin 20 permits of securing the parts together by means of the nuts 23 without danger of clamping the stub frog between the upright portions 16 to a degree that would result in binding. It will 105

be noted that the lengths 10 slope inwardly from their opposite end portions so as to permit of bracing the stub frog at its pivotal 110

115

point as shown in Figure 4. The upright portions 16 between the ends of the rail sections are connected together by bolts 24 which pass through slots in the web of the 5 stub frog *a* and the nuts 25 screwed on the opposite ends of the bolts 24 serve to tighten these. Sleeves 26 which surround the pins and bear on the upright portions 16 operate to prevent distortion of the upright portions 10 in the operation of tightening the nuts. The opposite end portions of stub frog *a* are sloped inwardly, as indicated by 27 in Figures 5 and 6. With this construction any elongation which may occur in the stub frog 15 *a* and manifest itself in the form of a burr at the ends of the head 28 or a defect in manufacture of the base 29, either of which would interrupt free swinging movement of the stub frog, will be prevented. The angular shaped guard plates 30 and 31 which are secured to the web 32 of the stub frog *a* are movable therewith. These members are formed of sheet metal and their horizontal side portions extend laterally outward 20 through the intervening space between the head and the upper ends of the upright portions 16 of the tie. By referring to Figure 1, it will be noted that the horizontal side portions 32' conform to the diagonally opposed tapered spaces or pockets 33 which are presented between the stub frog *a* and the diagonally opposed upright side portions 16 when the stub frog *a* is in either of its adjusted positions with respect to the ends of 25 the track sections 5, 6, 7 and 8. With this construction, it will be seen that the aforesaid pockets 33 are closed by the portions 32' which operate to effectively prevent the entrance to the pockets of foreign substances 30 such as snow, roadbed material, objects falling from passing cars, and the like, which would operate to prevent swinging movement of the frog *a*. The usual heel blocks 34 are interposed between the end portions of 35 the sections 5, 6, 7 and 8, and are connected to the rail sections and to the tie by the bolts 18.

In Figure 7, the device of this invention is shown as used in connection with an 50 ordinary switch. For purposes of illustration, I have shown the tie bars 35 as being arranged on the outer sides of the rails 36 of the main track and connected thereto by bolts. The end portions of the tie bars on 55 the left of Figure 1, are provided with fish plates 37 and the heel blocks 38 are interposed between the end portions of the main line 36 and turnout rails 39. The guard plates 40 are similar in construction 60 to the guard plates 30 and are constructed and arranged so as to extend over and enclose pockets 41 which exist between the tie bars 35 and the track sections 42 and 43 of the stub switch, when the same is in either 65 of its adjusted positions with respect to the

main line and turnout rails 36 and 39. It will be noted by reference to Figures 10 and 11 that the tie bars 35 may be formed of sections of old track rail of less height than the track sections 36 and 39. In fact the tie bars in the form of the invention as shown and described, may be formed of material of any suitable type.

From the foregoing, it will be observed that the present construction contemplates the satisfactory use of both a stub switch and a stub frog without the attendant defects that have heretofore existed in the use of stub switches and frogs and which were largely instrumental in discarding the stub switch and stub frog from the practice of modern railway track construction. It will be noted that the stub rail sections constituting the switch or frog of this invention, are of uniform strength throughout their lengths as distinguished from structures wherein the sections are tapered and, at the same time, the dangerous facing points had with tapered sections, are eliminated. The tie bars by their construction and arrangement positively prevent creeping of the track sections with respect to the stub switch or frog sections. It will be further noted that the guard plates in addition to functioning as closures for the pockets 33 and 41, operate to increase the transverse strength of the stub rail sections and also increase resistance to overturning thereof on account of the bearing afforded for these by the tie bars. It will be further noted that the adoption of the stub rails eliminates the use of risers now required in point switches to raise the overhangs of the wheels over stock rails; therefore, and on account of the tread surfaces of the stub frog or stub switch being in a plane with the surface of the track rails, easier and more noiseless riding will be had.

In the form shown in Figures 10 and 11, a lock is provided for securing the rails 42 and 43 of the stub switch in any of their adjusted positions. The lock shaft 44 is carried by the switch rails 42 and 43, as shown in Figures 10 and 11. Suitable bearings 45 depending from the switch or stub sections are provided for supporting the lock shaft 44 and permitting the rotation thereof when turned by the usual operating handle, not shown. At suitable spaced intervals the lock shaft is provided with radial extensions 46 of a length conforming to the transverse lengths at the bases of the pockets 33 and 41 and thereby engage with the base portion of one of the stub switch rail sections and the adjacent tie bar so as to positively prevent lateral movement or displacement of the parts. Referring to Figure 10, it will be noted that the extension 46 on the right engages the tie bar 35 and the switch section 42 and, at the same time, one of a pair of 130

extensions 47 arranged opposite to the extensions 46 engages the tie bar 35 on the opposite side of the switch. In Figure 11 the lock shaft 44 is turned into the reverse position and also the stub switch rails and here the extension 46 on the left and the extension 47 on the right operate on their respective sides of the switch. In this connection the lock shaft 44 acts also as the throw-rod 10 for the switch, the collar 50 secured to said shaft operating to shift the switch rails when the shaft is moved endwise. In Figure 1, the locking shaft 44 is connected to the tie bar 35 and a throw-rod 48 connected 15 to a bracket 49 carried by the guard plate is employed for shifting the frog. Any of the common forms of instrumentalities may be employed for operating the throw-rod and the lock shaft to operate from one operation 20 of the switch lever, not shown.

Although I have shown and described one embodiment of my invention, it is to be understood that the same is susceptible of various changes; and I reserve the right to 25 employ such as may come within the scope of the appended claims.

I claim:

1. In a railway switch the combination of a pair of stationary track rails arranged in endwise spaced relation, a laterally adjustable switch rail interposed between said stationary track rails and movable into and out of alinement therewith, a rigid tie bar extending in the direction of the length of the 30 space between said stationary rails and offset from the longitudinal planes of the treads of said rails, and means immovably securing the opposite ends of the tie bar and the adjacent ends of the stationary rails one to the other whereby variation is prevented in the 35 length of the space between said stationary rails and a stop provided for limiting the movement of the switch rail.
2. In a railway switch, the combination of a pair of stationary track rails arranged in endwise spaced relation, a turn-out track rail disposed alongside of one of said stationary track rails, a laterally adjustable switch rail interposed between said stationary 40 rails and movable into alinement therewith and into alinement with the turn-out rail, a rigid tie bar extending in the direction of the length of the space between said stationary rails and having an end portion offset from the longitudinal planes of the treads of said rails, and means immovably securing the opposite ends of the tie bar and the adjacent ends of the stationary rails one to the other, whereby variation is prevented in the 45 length of the space between said stationary rails and a stop provided for limiting the movement of the switch rail.
3. In a railway switch, the combination of a pair of stationary track rails arranged in endwise spaced relation, a turn-out track rail 50 disposed alongside of one of said stationary track rails, an adjustable switch rail interposed between said stationary track rails and movable into alinement therewith and into alinement with the turn-out rail, a rigid tie bar disposed alongside the switch rail and disposed in spaced relation thereto and connected to all of said track rails and a guard plate disposed over the space between the switch rail and the tie bar.
4. In a railway switch, the combination of a pair of stationary track rails arranged in endwise spaced relation, a pair of stationary turn-out track rails disposed alongside the 55 first named rails and also arranged in endwise spaced relation, a switch rail adjustably secured in the space between the ends of all of said rails, a pair of rigid tie bars extending in the direction of the length of the 60 said space and offset outwardly from the longitudinal planes of the threads of the said rails, and means immovably securing the opposite ends of the tie bars to the adjacent ends of all of said rails, whereby variation is prevented in the 65 space between said stationary rails and stops provided for limiting the movements of the switch rail.
5. In a railway switch the combination of a pair of stationary track rails arranged in endwise spaced relation, a pair of stationary turn-out track rails disposed alongside the first named rails and also arranged in endwise spaced relation, a rigid tie bar, a switch rail disposed in the space between the adjacent ends of all of said rails and pivotally connected to the tie bar, the said tie bar extending in the direction of the length of the 70 space between the adjacent ends of said rails and having its opposite ends rigidly secured to the webs of the stationary and the turn-out rails whereby variation in the length of the 75 space between all of said rails is prevented.
6. In a railway switch, the combination of a pair of stationary track rails arranged in endwise spaced relation, a turnout track rail disposed alongside of one of said stationary track rails, an adjustable switch rail interposed between said stationary track rails and movable into alinement therewith and into alinement with the turnout rail, and a rigid tie bar disposed alongside the switch rail and connected to all of said track rails and a guard plate disposed over the space between the 80 switch rail and the tie bar.
7. In a railway switch, the combination of a pair of stationary track rails arranged in endwise spaced relation, a turnout track 85 rail disposed alongside of one of said stationary track rails, an adjustable switch rail interposed between said stationary track rails and movable into alinement therewith and into alinement with the turnout rail, and a rigid tie bar disposed alongside the switch rail and connected to all of said track rails and a guard plate disposed over the space between the switch rail and the tie bar.

rail disposed alongside of one of said stationary track rails, an adjustable switch rail interposed between said stationary track rails and movable into alinement therewith and into alinement with the turnout rail, and a rigid tie bar disposed alongside the switch rail and disposed in spaced relation thereto and connected to all of said track rails and a guard plate carried by the switch rail and movable therewith and extending over the space between the switch rail and the tie bar.

8. In a railway switch, the combination of a pair of stationary track rails arranged in endwise spaced relation, a turnout track rail disposed alongside of one of said stationary track rails, an adjustable switch rail disposed between said pair of stationary track rails and movable into alinement with these and into alinement with the turnout rail, a rigid tie bar connected at its opposite ends to the said stationary track sections and disposed in spaced relation to the switch rail

and a movable locking device adapted to engage the switch rail and the tie bar in the space therebetween.

9. In a railway switch, the combination of a pair of stationary track rails arranged in endwise spaced relation, a turnout track rail disposed alongside of one of said stationary track rails, an adjustable switch rail disposed between said pair of stationary track rails and movable into alinement with these and into alinement with the turnout rail, a rigid tie bar connected at its opposite ends to the said stationary track sections and disposed in spaced relation to the switch rail and a movable locking device adapted to engage the switch rail and the tie bar in the space therebetween when the switch rail is in one of its adjusted positions and further adapted to engage the tie bar only when the switch rail is in another of its adjusted positions.

MICHAEL S. HOUSKEN.
